(57) **CLAIM**

I claim the ornamental design for a trucker's safe-to-pass courtesy light, as shown and described.

DESCRIPTION

FIG. 1 is a perspective view of a trucker's safe-to-pass courtesy light showing my new design;

FIG. 2 is a front elevational view thereof;

FIG. 3 is a rear elevational view thereof; and,

FIG. 4 is a side elevational view thereof, the elevational view of all other sides being identical thereto.

1 Claim, 3 Drawing Sheets

FIG. 1

FIG. 4.

FIG. 2.

FIG. 3
